Specification of Letters Patent.

Patented May 1, 1917

Application filed April 4, 1913. Serial No. 758,775

To all whom it may concern:

Be it known that I, JAMES POWERS, a citizen of the United States, residing in New York city, in the county of New York and State of New York, have invented certain new and useful Improvements in Analyzing and Recording Mechanisms, of which the following is a specification.

My present invention relates to machines 10 of the same general character and having similar objects to that illustrated and described in my pending application, Serial No. 698887, filed May 22, 1912, and consists in an improved key action and operating 15 means therefor which, although within the scope of said application, constitutes such an improvement in the art and so increases the speed and precision of action of such machines and reduces their bulk, weight and 20 cost as to constitute, in view of the state of the art, a valuable, new and patentable invention, which consists primarily in the substitution, in my analyzing and recording mechanisms, of rack-and-pinion transmission 25 sion in lieu of the rocker arms of said application, and secondarily of divers improvements thereby made practicable.

As in said application, I provide a suitable main frame; a main shaft suitably mounted therein to which I fix cams for operating the several members of the apparatus; a card supply magazine or hopper and an analyzed-card bin, card plates forming a card-way and perforated with registering holes in digital series, corresponding with digital series of record cards; card-feed means adapted to feed cards, one at a time, from the hopper to and through the card way and into the bin; a card-stop; a vertically reciprocating pin box frame operable by cams on the main shaft, in parallel guides on the main frame and parallel pin box ways on said frame; a plurality of pin boxes (illustrated as two) slidably mounted and fixable in adjusted position on said ways and moving with said frame; a plurality of digital series of pins in said boxes, each series consisting in nine pins corresponding with the digits, spaced correspondingly with and adapted to register with series of holes in the card-way plates and with digital series on record cards and a hole in one or more of said card series; a plurality of adding machines (two) suitably fixed on the main frame; and a like plurality of analyzing

ing and recording mechanisms operably connected with cams on the main shaft and thereby timed in their operation relatively to the operations of the pin-boxes and their pins, and each adapted to analyze statements recorded in perforations in cards and in pins extending through said perforations and to cause the result of such analysis to be recorded by an adding machine,—each series of analyzing elements being adjustable in the machine and fixable in adjusted positions coöordinated with positions of the pin-boxes and with groups of digital series (some, it may be, perforated, each with one hole) of record cards recording statements to be analyzed and recorded; and positioning means adapted to enable the operator to quickly and accurately locate the adjustable elements in coöordinating positions.

In the drawings, Figure 1 is a partial plan showing the accounting machine proper with its card magazine broken off, and my analyzing elements; on the right a broken plan illustrating several of my selecting and recording elements and an adding machine; and on the left, broken transmission elements indicating that like mechanisms, not illustrated, are located to that side: Fig. 2 is a partial side elevation corresponding with Fig. 1; Fig. 3 is a transverse section on the line 3—3 of Figs. 1 and 2, corresponding with my analyzing elements; and, Fig. 4 is a similar section on the line 4—4 of Figs. 1 and 2, corresponding with my recording elements. 75 80 85 90

Fig. 13 is a fragmentary top plan view of the guideway for the analyzer carriage. 110

In the following description reference numerals, wherever possible, refer to like parts or parts of similar functions to parts so designated in my aforesaid application.

5 In the practice of my invention, I provide a main frame 1 and accounting machine elements such as described in the application referred to, comprising (besides elements not referred to) a main shaft 19, 10 suitably mounted in bearings in said frame and connected with a source of power; pairs of cams fixed on said shaft, respectively, pin-box operating cams 18 containing cam grooves 17, retractor cams 38 and recording platen cams 80; fixed on said frame 1, 15 a card-supply hopper 44, an analyzed-card bin 144 and located between them, a pair of horizontal perforated plates, respectively 28 and 29, having a plurality of 20 digital series of registering perforations with nine holes in each series, corresponding with the digits and said series spaced in consonance with digital series of numbers (some perforated) in record cards; a 25 card-path between said plates; a card stop 31 comprising a pair of stop-fingers 31^a on a shaft 31^b operably connected with the main shaft and adapted to stop a card in registering position in the card-way between the card-plates 28 and 29; a card-feed slide or picker 43, adapted to pick one card at a time from the hopper 44 and advance it to a card feed mechanism (generally indicated by 30) comprising feed 35 rolls on shafts suitably mounted and operably connected with the main shaft 19; a vertically-reciprocating jig or pin-box table 11^a provided with parallel guides engaging corresponding guides on the main 40 frame 1, movable therein by the engagement of rollers 15 and 16 (revolvably mounted on said jig) with the cam-grooves 17 of the cams 18, and adapted for the adjustable mounting of pin boxes 26 and 27 45 and comprising horizontal parallel pin-box ways 11 and 12, exterior positioning racks 24 thereon and downwardly-extending arms at the ends thereof united in pairs, 13 and 14, by transverse bars 13^a and 50 14^a; and a plurality of pin-boxes (illustrated as two) 26 and 27 suitably mounted on the jig ways 11 and 12, and each of which comprises a pair of perforated pin guide plates, 7 and 8,—separators, 9 and 55 10, to which said plates are joined (with their ends projecting to form mounting guides by which said boxes are mounted as aforesaid),—a U-shaped upper, perforated positioning plate 22, the body of which is 60 parallel with the pin-guide plates 7 and 8 and the down-turned outer arms 23, of which are provided with positioning rack teeth corresponding with the teeth of the positioning racks 24 of the jig ways 11 and 65 12,—the perforations in the plates 7, 8 and 22 being in digital series adapted to register with the aforesaid holes in the card-plates 28 and 29, and with digital series (some perforated with one hole) of record cards,—series of pins, 20, movable in said perforations and each having an exterior head 21, which limits its downward motion when its lower end projects sufficiently below the lower card plate 29,—and screws, 25, by which the pin boxes 26 and 27 may be secured in adjusted position on the ways 11 and 12.

On suitable side extensions 1^a of the frame 1, I locate a pair of adding machines A and A¹ (the latter not illustrated) and I provide duplicate, selective, analyzing and recording mechanisms R and R¹ (the latter not illustrated) adapted to be operated synchronously but independently by a suitable operative connection with the main shaft 19 and each adapted to co-act with the above-described accounting machine elements, to analyze one statement out of a plurality of statements recorded on a card by a perforation in each of a group of digital series of said card and to select and operate the proper keys of the digital key-series of the adding machine.

Each analyzing and recording mechanism R comprises a series of independently operable, selective key action, K. Each key action K comprises an analyzer 32, a selector 68, a digital series of (nine) striking keys 48, each adapted to strike one key 58 of a digital key series of the adding machine A, a transmission T adapted to connect and synchronize the motions of the analyzer 32 and selector 68 and means to operably connect and disconnect the selector with and from any selected key of the striking series.

The analyzers of the series comprised in an analyzing and recording mechanism R (or R¹) are operably mounted in a movable carriage 33, to the end that they may be suitably positioned, as a series, relatively to the series of pins 20 in a pin box 26 and to a statement-recording group of digital series on a record card.

The recording elements of the connected series on the contrary, operate in planes fixed by the mode of supporting said members on the frame 1; and the transmission shafts 86 are revolvably mounted but axially fixed in the carriage 33 and revolvable but axially movable in bearings, 93, in the frame 1 and slidably engage transmission elements (gears 95) directly connected with the selectors 68. Each analyzer 32 is preferably a rectangular bar provided with a finger, 34, the contact face of which is concave, so that it may engage with and be stopped and accurately positioned by a pin 20 projecting below the card-support plate 39 and with a rack, 32^a, formed in its under face.

The analyzer carriage, 33, is provided with mounting heads 33^a and mounting slots 33^b therein for mounting the analyzers; a foot 87 and transverse therein a V guide 87^a and a half dovetail guide 87^b which engage corresponding guides 98^a and 98^b on a rail or way 98 connected with the machine frame 1 on which the carriage is slideable, and an arm 87^c and screw 87^d engaging a tapped hole therein and adapted to clamp the carriage in adjusted positions on said guides; and a series of bearings 85, in which I revolvably mount and suitably axially position the transmission shafts 86 of the series. I also provide a track 47 connected with the machine frame, adapted to support the out-hang of the frame 33, on which I revolvably mount rollers 45 to engage said track.

I provide a positioning engagement between the carriage 33 and the way 98 to enable the operator to quickly and accurately position the former relatively to an adjusted pin-box and comprising a series of conical sockets 105 in said way, each corresponding in position with a pair of teeth in the positioning racks 24 and a positioning pin 104 located in a socket formed in the carriage foot, 87, advanced by a spring and provided with a conical head 104^a corresponding with the sockets 105, which head is so oblique that the pin is retractable by the sliding of the carriage. When the carriage is shifted the pin-head 104^a plays in and out of the sockets 105; and when the carriage is nearly adjusted, the pin-head engages a socket and thereby enables the operator to set the carriage with precision.

The selectors 68 are preferably rectangular bars and are slidably mounted in series of guide slots 68^a formed in the machine frame 1, are severally independently advanceable by a spring 82, strained between a lug 83 on the selector and a pin 84 on the machine frame and each is provided with a rack 68^b cut in its under face and a plunger 74, slideable in a vertical bearing in the selector head and having a lower head 75 pressed down by a spring 76, against a platen 77, to be described hereafter.

The striking keys 48 which are levers in series corresponding with the selectors and with digital series of keys 58 of the adding machine A, are pivotally mounted on the main frame 1 by means of pivot rods 57, and suitably separated or spaced thereon, the keys in a series being alternated or staggered in two parallel adjacent planes, so that they may be individually operated without fouling one another; their several striking ends are located just above the extended positions of the several keys 58 of a digital adding-machine series and their opposite ends are each pivotally connected with a pendent or key rod 59 of a series arranged in the same vertical plane with a

selector 68 and adapted to be reciprocated in guides formed in a pair of guide plates 81^a and 81^b, (the latter their positioning plate) to be depressed by a spring 81, strained between the upper plate 81^a and a collar 81^c on said rod, said springs normally holding said rods depressed and so positioned by the guide plates 81^a and 81^b and the contact of their collar 81^c with the latter, that their lower ends are alined just above the line of traverse of the top of the selector plunger 74 and individually above the series of selective positions of said plunger.

Beneath the series of key rods 59 and the possible positions of the selector plungers 74, I locate a platen 77, vertically reciprocable and guided by engaging parallel guides formed on its end posts 77^a and engaging guides 78 on the frame 1, and operated by means of a pair of cams 80 on the main shaft 17 and cam rollers 79 on the platen arms engaging therewith.

In the operation of my apparatus, the advance of a selector 68 is spring actuated (by spring 82), synchronous with the advance of its connected analyzer 32 and arrested by the arrest of said analyzer. If the latter is not arrested by contact with a pin 20 which has registered and passed through a card-perforation, the selector advances its plunger 74 beyond the key rod series, but if the analyzer be arrested by such a pin 20, the selector is also arrested with its plunger 74 in register with one or other of the key-rod 59. All the selectors being thus and synchronously operated, the platen 77 is lifted by the revolution of the cams 80 and lifts the selector plungers. Those of the latter which are in register with key rods 59 lift them, and operate the connected striking keys 48 which strike the corresponding adding machine keys 58 and cause the adding machine to record the statement contained in the digital series of the record card, as analyzed by pins 20 registering with card perforations and analyzers 32, each co-acting with such a pin. Those selector plungers whose connected analyzers found no fact recorded by a projecting pin 20, being fully advanced beyond and clear of the key-rod series, are idly reciprocated.

The transmission of each key action comprises a shaft 86 revolvably mounted and axially fixed in a bearing 85 in the carriage 33, a gear wheel 88 fixed on said shaft in mesh with the rack of the analyzer 32 and a gear wheel 95 axially fixed in a supplemental frame 1^b attached to the main frame 1 but revolvable with the shaft 86 which engages and which is slideable through said gear by means of a suitable engagement 95^a illustrated as a spline in the wheel engaging a corresponding way in the shaft.

The analyzer 32 and selector 68 of each key action of the series, being connected 130

and synchronized in their motions by an independent transmission T, are synchronously advanceable by their spring 82, independently of the other key-actions of the series, the limit of their advance being such that when fully advanced the finger 34 of the analyzer 32 is beyond the last pin 20 (corresponding with the digit 9) of the digital pin box series with which it is co-acting and the selector plunger 74 is beyond the last key rod 59 (also corresponding with the digit 9) of the digital striking key series; and when the platen 77 is next lifted, no adding machine key 58 in the corresponding adding machine digital series will be struck, and it will record a naught or zero, for said series.

I provide a retractor F, such as described in said application, operably connected with the main shaft 19, adapted to control the advance of the key actions K until they are arrested by contact of their analyzer fingers 34 with pins 20 or when not so arrested, throughout their advance, to simultaneously initiate the retraction of all fully advanced actions and to pick up pin arrested ones, fully retract all of them simultaneously and to hold them retracted during a proper portion of the function-cycle. The retractor F is a rocking frame pivotally mounted on the machine frame 1 and comprises a pair of end mounting bars 35, a retracting bar 39 in the free ends thereof and adapted to contact with the inner ends of the analyzers 32 and retract them and a rod 42^a, on which I pivot one end of a link 42, the opposite end of which is pin-connected with the sliding card feed or picker 43.

The retractor F is rocked by a pair of cams 38 on the main shaft 19, being operably connected therewith by a pair of slotted links 36, each pivotally connected with a retractor mounting bar 35, provided with a slot 36^a which envelops the shaft 19 and by the engagement of its sides therewith, transversely positions and guides its own reciprocation and with a revolvably mounted roller 37 which engages a cam 38.

It will be understood by reference to the drawings, that the elements of the duplicate analyzing and recording mechanism R¹ are similar to those above described for the like mechanism R, save that their respective analyzer carriages 33 are left and right hand as to the disposition of their shafts.

The operation of my apparatus is as follows:

It being desired to analyze and record statements of similar facts recorded on record cards by one perforation in each series of a group of digital series on each such card,—or to so treat two statements so recorded on each such card,—the pin boxes are elevated to free their pins from the pin plates 28, the screws 25 of the pin box 26

or of both pin-boxes are loosened, the engaged positioning rack teeth of the positioning racks 24 and of the plates 22 are separated and the pin box or boxes adjusted in position relatively to the position, when 76 said record cards fed into the card way, of the record digital series on said cards, and the screws 25 are tightened, locking said engaging rack teeth and accurately positioning the pin box or boxes. The carriage or 75 carriages 33 are then adjusted in position, being accurately set by the engagement of the positioning pin head 104^a with a socket 105 in the way 98 and clamped thereto by the screw 87^a, the several axial planes of 80 the analyzers 32 and corresponding series of pins 20 being common to both.

The revolution of the main shaft and cams raises and lowers the pin boxes 26 and 27 and the platens 77; rocks the retractor 85 F, thereby retracting and permitting the spring-actuated advance of the analyzers and selectors, and reciprocating the card picker 43; rocks the card-stop 31; and operates the card feed 30. The functionings 90 of the cams are so timed that during the rise of the pin boxes (by which the card way is cleared of pins) the card-stop is set, the card picker and card-feed pick a card from the hopper and advance it to operative 95 position (fixed by the card stop), the analyzers and selectors are retracted, the platens rest in their lowest positions, the striking keys are retracted and the adding machine keys are extended, all becoming 100 ready to perform their functions.

When the pin-boxes descend, the points of the pins of their digital series register with corresponding points in the digital card series. Those pins which find no record perforations in the card series are arrested; but those which find such perforations extend their ends through the holes in the card-support plate 29 and reproduce, below said plate, the statement recorded in 110 the card perforations. Immediately thereafter the retractor is retired, thereby permitting spring actuated advance of the analyzers and selectors (and also retracting the card picker). Those analyzers which 115 find no pins in their path, advance with the retractor to the limit of its motion and their connected selectors advance with them to zero position; but those analyzers which find and are arrested by pins severally arrest their connected selectors with the plungers thereof in selected positions which reproduce the same record, each selector plunger being then operatively beneath a key-rod of the corresponding striking-key 125 series.

The platens 77 are then lifted by their cams, and lift the selector plungers and such key-rods as register with selector plungers, which swing their connected striking keys 130

which in turn strike their adding machine keys and depress and set them, ready to reproduce in the adding machine, in readable form, the statements recorded in the card.

6 At such times non-registering selector plungers and key rods, respectively, move idly and remain at rest, and the corresponding adding-machine keys remain extended and cause no record.

10 Following the above described operations, the platen is lowered, the just-operated striking keys and their key rods are retracted, the shaft of the adding machine is operated to cause it to print said record and extend its keys, the card stop is retired opening the card way, the card feed 30 advances the card from the card way to the analyzed-card bin, the card stop is again set to close the card way, the retractor is advanced, retracts the analyzers and selectors and advances the card picker and another card and the apparatus is ready to perform another cycle.

15 It will be seen that when an analyzer 32 is moved its rack 32¹ revolves the engaging gear 88¹ and the shaft 86 and selector gear 95, and because of the engagement of said gear with the selector rack, synchronously moves the selector 68; or vice versa; and that this mode of operation is much more precise 20 and certain and less impaired by clearances, backlash and flexure of the members than the rock-shaft-and-arms transmission of my above application; and also that the unital transmission shafts herein described are 25 much superior in their operations to, and at the same time cheaper than, the two-part extensible shafts of the former application.

30 I illustrate the action shafts 86 as axially engaged and slidable with the carriage 33. 40 Action shafts axially fixed in the machine frame and over which the carriage and analyzers severally, slidably engaged with said shafts could slide, would operate equally well if I used only one analyzing and recording mechanism; or shafts so fixed and extending to the central plane of the machine would satisfactorily operate duplicate mechanisms provided the carriages were never moved so far as to disengage the analyzers 45 from the shafts. But the construction illustrated increases the range of action of an apparatus employing duplicate mechanisms R and R¹ because one carriage may be located at the outer limit of its range and the 50 second located in juxtaposition to the first, thus enabling my duplicate apparatus to analyze and record any two statements properly recorded in perforations of a card, however those statements may be located thereon.

55 60 I have used throughout, the term "adding machine" because such apparatus is primarily intended for the production of printed numerical statements, generally tabular, such as are produced by adding machines. 65 But I might adapt my apparatus to use in

connection with any record-printing machine of a generally similar character; and where I refer in the claims to such apparatus I use the broader term.

Having thus described my invention, I claim:—

1. An action for analyzing and recording mechanisms of accounting machines comprising an analyzer having a plurality of rack bars and pinions meshing therewith, a selector having a plurality of rack bars and pinions meshing therewith, shafts connecting the pinions of the analyzer and the pinions of the selector, means for driving the said pinions, a recorder, and means carried by the selector for causing an operation of the recorder. 75

2. An action for analyzing and recording mechanisms of accounting machines, comprising an analyzer having a plurality of rack bars and pinions meshing therewith, a selector having a plurality of rack bars and pinions meshing therewith, connecting means between the pinions of the analyzer and the pinions of the selector, means for driving the pinions of the analyzer, a recorder, and means carried by the selector for causing an operation of the recorder. 85

3. An action for analyzing and recording mechanisms of accounting machines, comprising an analyzer having a plurality of rack bars and pinions meshing therewith, a selector having a plurality of rack bars and pinions meshing therewith, connecting means between the pinions of the analyzer and the pinions of the selector, means for normally driving the pinions, means for retaining said driving means, a recorder, and means carried by the selector for causing an operation of the recorder. 95

4. An action for analyzing and recording mechanisms of accounting machines, comprising an analyzer having a plurality of rack bars and pinions meshing therewith, means for driving the said pinions, means for limiting the movement of the said rack bars, a selector having a plurality of rack bars and pinions meshing therewith, the pinions of the analyzer and the pinions of the selector connected whereby the movement of the former transmits an equivalent movement to the latter, a recorder, and means carried by the selector for causing an operation of the recorder. 100 110 115

5. An action for analyzing and recording mechanisms of accounting machines, comprising an analyzer having a plurality of rack bars and pinions meshing therewith, means for driving the said pinions, stops carried by the said rack bars providing means for limiting their movement, a selector having a plurality of rack bars and pinions meshing therewith, shafts connecting the pinions of the analyzer and the pinions of the selector whereby the rotations of the 120 125 130

former are transmitted equivalently to the latter, a recorder, and means carried by the selector rack bars for causing an operation of the recorder.

5. 6. An action for analyzing and recording mechanisms of accounting machines, comprising an analyzer having a plurality of rack bars and pinions meshing therewith, means for driving the said pinions, a selector having a plurality of rack bars and pinions meshing therewith, shafts connecting the pinions of the analyzer and the pinions of the selector whereby a movement of the former is transmitted to the latter, a recorder, and means carried by the selector for causing an operation of the recorder.

7. An action for analyzing and recording mechanisms of accounting machines, comprising an analyzer having a plurality of rack bars and pinions meshing therewith, means for driving the said pinions, a selector having a plurality of rack bars and pinions meshing therewith, means for driving the said pinions, a selector having a plurality of rack bars and pinions meshing therewith, shafts connecting the pinions of the analyzer and the pinions of the selector whereby a movement of the former is transmitted to the latter, a recorder, keys arranged to operate it, and means carried by the selector for causing the said keys to move for operating the recorder.

8. An action for analyzing and recording mechanisms of accounting machines comprising an analyzer, a selector, gear teeth on the analyzer and on the selector, a shaft, pinions on said shaft respectively engaged with the gear teeth on the analyzer and on the selector, and a series of keys, the selector and the series of keys operative substantially in a fixed plane, the analyzer adjustable into and operative in a plurality of planes, the gear engaged with the analyzer movable with it, and a sliding connection between one of said gears and said shaft.

9. An action for analyzing and recording mechanisms of accounting machines comprising an analyzer, a selector, gear teeth on the analyzer and on the selector, a shaft, pinions on said shaft respectively engaged with the gear teeth on the analyzer and on the selector, a series of keys, the selector and the series of keys operative substantially in a fixed plane, the analyzer adjustable into and operative in a plurality of planes, the shaft and the gear engaged with the analyzer axially fixed relatively to said analyzer, the gear engaged with the selector axially fixed, and a sliding connection between said shaft and the gear engaged with the selector.

10. An action for analyzing and recording mechanisms of accounting machines comprising an analyzer, a selector, racks on the analyzer and on the selector, a shaft, pinions on said shaft respectively engaged with

the gear teeth on the analyzer and on the selector, a series of keys, the selector and the series of keys operative substantially in a fixed plane, the analyzer adjustable into and operative in a plurality of planes, the shaft 70 and the gear engaged with the analyzer rack axially fixed relatively to said analyzer, the gear engaged with the selector rack axially fixed; and a sliding connection between said shaft and the gear engaged with the selector 75 rack.

11. An analyzing and recording mechanism for accounting machines comprising a plurality of actions, and, comprised in each such action, an analyzer, gear teeth on said analyzer, a selector, gear teeth on said selector, a shaft, pinions mounted on said shaft and engaged with the teeth on the analyzer and on the selector, a series of keys; a movable carriage on which the analyzers of the 85 plurality of actions are mounted, the gears engaged with said analyzers are revolvably mounted but axially fixed relatively to said carriage and its action shafts are similarly mounted and fixed; and an axially adjustable engagement between the shaft and selector gear of each action.

12. An analyzing and recording mechanism for accounting machines comprising a plurality of actions, and, comprised in each 95 such action, an analyzer, a rack on said analyzer, a selector, a rack on said selector, a shaft, pinions mounted on said shaft and engaged with the rack on the analyzer and on the selector, a series of keys; a movable 100 carriage on which the analyzers of the plurality of actions are mounted, the gears engaged with said analyzers are revolvably mounted but axially fixed relatively to said carriage and its action shafts are similarly 105 mounted and fixed; and an axially adjustable engagement between the shaft and selector gear of each action.

13. An analyzing and recording mechanism for accounting machines comprising a 110 plurality of actions, and, comprised in each such action, an analyzer, gear teeth on said analyzer, a selector, gear teeth on said selector, a shaft, pinions mounted on said shaft and engaged with the teeth on the 115 analyzer and on the selector, a series of keys; a movable carriage on which the analyzers of the plurality of actions are mounted, the gears engaged with said analyzers are revolvably mounted but axially fixed relatively to said carriage and its action shafts are similarly 120 mounted and fixed; an axially adjustable engagement between the shaft and selector gear of each action, parallel guides parallel with said shafts formed on 125 said carriage and adapted to engage corresponding guides on a machine frame, and fixing means adapted to fix said carriage in desired positions on said guides.

14. An analyzing and recording mecha- 130

- nism for accounting machines comprising a plurality of actions, and, comprised in each such action, an analyzer, gear teeth on said analyzer, a selector, gear teeth on said selector, a shaft, pinions mounted on said shaft and engaged with the teeth on the analyzer and on the selector, a series of keys; a movable carriage on which the analyzers of the plurality of actions are mounted, the gears 5 engaged with said analyzers are revolvably mounted but axially fixed relatively to said carriage and its action shafts are similarly mounted and fixed; an axially adjustable engagement between the shaft and selector gear of each action, parallel guides parallel with said shafts formed on said carriage and adapted to engage corresponding guides on a machine frame, and clamping means adapted to clamp said carriage in desired 10 positions on said guides.
15. An action for analyzing and recording mechanisms of accounting machines of that type in which statements recorded on cards by means of perforations are registered by pins passing through such perforations, said action adapted to be actuated by actuating means connected with the accounting machine to select and strike keys of a record-printing mechanism, and said 20 action comprising an analyzer, a selector, a rack and pinion gearing transmission, and a series of keys, said analyzer adapted to be positioned by contact with such a pin, said transmission adapted to position said selector correspondingly with positions of said analyzer, and said selector adapted to be so positioned in selective and operable positions relatively to individual keys of said key 25 series and to cause the operation thereof.
40. 16. An analyzing and recording mechanism for accounting machines of that type in which statements recorded on cards by means of perforations are registered by pins passing through such perforations, said mechanism comprising a plurality of actions each adapted to be actuated by actuating means connected with the accounting machine to select and strike keys of a record-printing mechanism, and each action 45 comprising an analyzer, a selector, a rack and pinion gearing transmission and a series of keys, the analyzer of each action adapted 50 to be positioned by contact with such a pin, the transmission thereof adapted to position the selector thereof with positions of said analyzer, and said selector adapted to be so positioned in selective and operable positions relatively to individual keys of the key series thereof and to cause the operation of said selected keys. 55
17. An action for analyzing and recording mechanisms of accounting machines of that type in which statements recorded on cards by means of perforations are registered by pins passing through such perforations, said action adapted to be actuated by actuating means connected with the accounting machine of a record-printing mechanism, and said action comprising an analyzer, a selector, a rack and pinion gearing transmission, and a series of keys, a movable carriage on which the analyzers of the plurality of actions are mounted, the gears engaged with said analyzers are revolvably mounted but axially fixed relatively to said carriage and the action shafts are similarly mounted but axially fixed, and an axially adjustable engagement between the shaft and selector of each action, the analyzer of each action adapted to be positioned by contact with such a pin, the transmission thereof adapted to position the selector thereof with positions of said analyzer, and said selector adapted to be so positioned in selective and operable positions relatively to individual keys of the key series thereof and to cause the operation of said selected keys. 60 65 70 75 80 85
18. An action for analyzing and recording mechanisms of accounting machines, comprising an analyzer having a plurality of rack bars and pinions meshing therewith, a selector having a plurality of rack bars and pinions meshing therewith, connecting means between the pinions of the analyzer and the pinions of the selector, resilient means for normally driving the pinions, means for retaining said driving means, a recorder, and means carried by the selector for causing an operation of the recorder. 90 95
